INVENTOR

Hubert L. Hamilton.
BY J. H. Weatherford
ATTORNEY.

UNITED STATES PATENT OFFICE.

HUBERT L. HAMILTON, OF LOUANN, ARKANSAS.

PILL TILE.

Application filed March 12, 1925. Serial No. 15,168.

To all whom it may concern:

Be it known that I, HUBERT L. HAMILTON, a citizen of the United States, residing at Louann, in the county of Ouachita and the

5 State of Arkansas, have invented certain new and useful Improvements in Pill Tiles, of which the following is a full, clear, and exact description such as will enable anyone skilled in the art to make and use the same.

10 My invention relates to pill tiles or slabs upon which druggist's prescriptions and the like are mixed or triturated and has for its object to provide a device of this character on which the pill mass or powder may be 15 mixed and thereafter be confined, spread out in a uniform layer and, if desired, be compressed prior to separation into a number of equal parts.

I accomplish this object as will be more 20 fully hereinafter set out in the drawings, specification and claims.

In the drawings:

Fig. 1 is a perspective view of the device.

Fig. 2 is a section on the line II—II of 25 Fig. 4.

Fig. 3 is a side view partially broken away showing a modified form of the device, and

Fig. 4 is a section on the line IV—IV of Fig. 2.

30 Fig. 5 is a section on the line V—V of Fig. 6, and

Fig. 6 is a perspective view of a modified form of the device.

Referring now to the drawings in which 35 the various parts of the device are indicated by numerals. The tile comprises a flap top slab 1 on which the materials may be mixed. This slab preferably has sides

2—2 and ends 3—3 projecting downward 40 therefrom forming a rectangular hollow tray disposed in an inverted position, and is slidably mounted in a tray having a bottom 4, sides 5—5 and an end 6 the opposite end being ordinarily left open. Secured to the

45 underside of the slab 1 of the tile are racks 7—7 disposed parallel to the sides 2—2. 8—8 are similar racks secured to the bottom 4 of the tray and projecting upward therefrom in alignment with the racks 7—7.

50 Disposed between these racks are pinions 9—9 which are secured to and turnable by means of a shaft 10 which projects through from side to side of the tile and tray and is provided with a knob or handle 11 by

55 which it may be rotated. 12 are aligned slots in the sides, 2—2 of the tile and 5—5

of the tray, in which the shaft 10 is free to slide. The end 6 of the tray may be provided with a scale 13 if it be so desired and the end 3 of the tile adjacent to the end 6 of the tray may be similarly provided with a scale, though this is not shown, nor often used.

In Fig. 3, I show a modification of the device in which the slab 1 is provided with the racks 7—7 which engage the pinions 9—9 similarly mounted on the shaft 10, but in which no corresponding racks 8—8 on the tray are used. In such case the sides 2—2 of the tile are provided with slots 70 12—12 but no such slot is provided in the sides 5, the shaft 10 in such case being journaled in the sides 5—5.

It will be noted that the pinion shaft 10 sliding in the slots 12—12 holds the pinions 9—9 in engagement with the rack 7—7 where one set of racks is used and similarly where two sets of racks are used, holds it in engagement with the racks 7—7 and 8—8.

In Figs. 5 and 6, 14 is a base or counter 80 on which the tray 4 rests and is slidable. The slab 1 rests as before in this tray and is slidable with reference thereto. In this case however the slab is shown solid instead of hollow as in the preceding figures. 15 is a 85 projection extending downward from the rear end of the slab and resting on the base 14. 16—17 are flanges or cleats extending upward from the base in front of and behind the projection 15 to prevent movement 90 of the slab relatively to the base. In this case the slab is grooved to receive the rack 7 which is shown integral with the slab. One centrally disposed rack may be used, or two spaced apart as desired. Where a heavy slab 95 is used, the weight of the slab serves to hold it down, and keep the rack in engagement with the pinion. In this form the slab may be readily removed for the purpose of 100 cleaning the tray.

The action of the device is as follows:

A pill mass or powder is mixed on the surface of the slab 1 in the usual manner. It is then moved forward into the channel formed between the end of the tile and the 105 end of the tray and the knob 11 is turned to shift the tile relatively to the tray and collect the pill mass between these ends. During this movement the end of the tile slides on the bottom 4 of the tray concentrating the pill mass or powder. This mass may then be leveled up in the channel and 110

compressed if it be so desired. Thereafter the pill mass may be divided into equal parts, the scale 13 serving to indicate the proper division and the parts be removed through the opening left in one of the sides 5 for that purpose.

It will be understood that further modifications may be made in the details of construction and I do not wish to be limited by 10 the structures shown except in so far as is required by the claims.

It will be noted in Figs. 1 to 4 inclusive the tile is moved, whereas in Figs. 5 and 15 6 the tray is moved. In both cases however it will be seen that irrespective of which moves the tile is slidably mounted in the tray, and that the tile and tray are slidable or shiftable relatively the one to the other.

Having now fully described my invention, 20 what I claim and desire to secure by Letters Patent in the United States is:

1. The combination with a tray, a pill tile slidably mounted therein, racks secured to the underside of said tile, corresponding 25 racks secured to said tray, a pinion shaft, pinions carried by and secured to said shaft, one disposed between each pair of said racks and engaging therewith, a knob on the end of said shaft for rotating the same and corresponding slots in the sides of said tray and pill tile to permit movement of said shaft.

2. The combination with a tray, having a bottom, sides and at least one end extending 35 upward from said bottom, of a pill tile slidably mounted in said tray, said tile comprising a mixing slab having depending ends and sides, said sides being longitudinally slotted, racks disposed parallel to said sides 40 and secured to the under surface of said tile, pinions, one engaging each of said racks, a pinion shaft disposed in said slots carrying

and secured to said pinions and means for turning said shaft.

3. The combination with a tray, comprising a bottom, sides and at least one end extending upward therefrom, said sides being longitudinally slotted, a pill tile slidably mounted therein, said tile comprising a mixing slab having ends and sides depending therefrom, said sides being provided with slots adapted to align with the slots in the sides of said tray, racks disposed parallel to said sides and secured to the under surface of said tile, corresponding racks secured to the upper surface of the bottom of said tray in alignment with said tile racks, pinions, disposed between said racks, one pinion between each tile rack and the corresponding tray rack and engaging therewith, a pinion shaft disposed in said slots carrying and secured to said pinions and a knob secured to said shaft outside of said tray.

4. The combination with a tray, a pill tile slidably mounted therein, a rack, secured to one of said members, and a pinion, carried by the other of said members, engaging with said rack, for shifting said tile relatively to said tray.

5. The combination with a tray having an upwardly projecting end, a pill tile slidably mounted in said tray, and means for shifting said tile relatively to said end.

6. The combination with a tray having an upwardly projecting end, a pill tile slidably mounted in said tray, a rack, secured to one of said members, and a pinion, carried by the other of said members, engaging with said rack for shifting said tile relatively to said end.

In testimony whereof I have hereunto set my name.

HUBERT L. HAMILTON
